UNITED STATES PATENT OFFICE.

HERBERT O. CRIPPEN, OF CHICAGO, ILLINOIS.

SPIKE RETAINER.

Application filed June 22, 1925. Serial No. 33,753.

This invention relates to improvements in spike retainers, and has for one of its principal objects the provision of retaining means for spikes or the like, particularly railroad spikes, whereby the spike, upon being driven into place in conjunction with the retaining means of this invention, will be securely maintained in desired position.

One of the important objects of this invention is to provide, in a spike retaining means or the like, an element which can be used in conjunction with an ordinary spike, nail, or screw, without any adaptation of the spike thereto, and which can be applied to the spike or nail and used therewith without extra labor.

Still another important object of this invention is to provide, in a retaining means particularly for railroad spikes, elements which automatically spread when the spike is driven so as to securely grip the material of the tie, and an additional element which is more or less automatically brought into retaining position with respect to the head of the spike.

Other and further important objects of the invention will be apparent from the disclosures in the accompanying drawings and following specification.

The invention, in a preferred form, is illustrated in the drawings and hereinafter more fully described.

In the drawings:

Figure 1 is a perspective view of the improved spike retainer of this invention.

Figure 2 is a perspective view showing the spike retainer as adapted to an ordinary railroad spike and about to be applied to a tie plate.

Figure 3 is a detail view, partly in section, showing the spike and retainer as driven into position in conjunction with a rail, tie, and tie plate.

Figure 4 is a perspective view illustrating a slight modification of the invention.

Figure 5 is a somewhat similar perspective view illustrating the modification shown in Figure 4 as applied to a wood screw or the like sometimes used in railroad construction.

As shown in the drawings:

The reference numeral 10 indicates generally the body of the improved spike retainer of this invention, comprising essen-

tially a metal plate bent into rectangular shape as shown, and with the bent-over ends slightly separated so as to form a slot 12.

Integral with the body 10 are a plurality of depending spur elements 14, preferably four in number, and with two on each side, as shown, the lower ends of these spur elements being pointed and formed straight on one side and slightly curved on the inner side, as shown at 16, so as to insure a spreading action when driven.

It will be noted that the lower edges of the body 10 are beveled, as at 18, so as to provide a cutting or penetrating edge, thereby insuring a more ready penetration of the material of the tie.

Integral with the body 10, and extending upwardly and outwardly therefrom, is a locking element 20, preferably in the form illustrated, and it will be noted that the point 22 at which the element 20 springs from the main body 10 is at the bottom of a notch or the like cut into the body 10, this arrangement providing for a more suitable conforming of the locking element 20 to the head 24 of the spike 26, and further, providing for a co-operation between the back of the member 20 and the corresponding portion of the opening in the tie plate 28, whereby the member 20 will be automatically bent upwardly from the position shown in Figure 1 to approximately a vertical position as the spike 26 is driven into the tie 30 through the tie plate 28.

The upwardly extending end of the locking member 20 can then be bent over into locking position with respect to the head 24 of the spike 26, as shown in Figure 3.

As the members 14 penetrate the material of the tie 30 the beveled or curved inside edges 16 will insure a spreading of the members 14 from the positions shown in Figures 1 and 2, into the outwardly diverging positions shown in Figure 3, whereby the locking element 20 is securely retained in position in the tie 30. The spreading of the members 14 is along separate outward paths independent of the course of the spike, and this spreading action compresses the grain of the wood so as to prevent any tendency of the tie to split.

The bending of the member 20 over the head of the spike will accordingly lock the spike into a fixed relation with respect to

the tie 30, thereby maintaining the rail 32 in practically immovable relation with the tie and the tie plate.

The modification shown in Figure 4 comprises a body member 34 substantially the same as the body member 10, but formed into a circular shape, as distinguished from rectangular, and is adapted to be applied to wood screws, nails, or the like of circular cross-section, one of which is illustrated at 36 in Figure 5. The outline of the outwardly extending integral locking member 38 is, in Figures 4 and 5, shown as somewhat circular to conform to the circular screw head or the like, but it will be obvious that the contour, shape, and construction of the co-operating elements may be varied as desired or necessary. In the event that it becomes necessary to remove a spike which has been locked by this device, the bent-over member 20 is pried rearwardly, allowing the spike to be raised slightly, after which a chisel or the like can be inserted into the opening 12 and the spike may then be withdrawn. The locking member may also in this manner be removed, if necessary.

It will be obvious that herein is provided a locking means for railroad spikes or the like, which, when used with a spike, will automatically act to retain the same in desired position and without any danger of the spikes pulling out or becoming loose, even under the most severe conditions of service. Further, the locking element may be economically manufactured and readily applied to the spikes, tie plates, and rails already in use without modifying the same in any way. Again, the operation being practically automatic, renders the device fool proof and insures its correct action under all circumstances.

I am aware that many changes may be made and numerous details of construction varied throughout a wide range without departing from the principles of this invention, and I therefore do not purpose limiting the patent granted hereon otherwise than as necessitated by the prior art.

I claim as my invention:

50 1. A spike retainer, comprising in combination, a body formed to encircle a spike, material gripping members extending from the body, a spike retaining element also integral with said body, and means for automatically spreading the material gripping elements upon application of the same.

60 2. A spike retainer, comprising in combination, a body formed to partially encircle a spike, material gripping members extending from the body, a spike retaining element also integral with said body, and means for automatically spreading the material gripping elements upon application

of the same, said means comprising curved inner faces on said material gripping elements.

3. A spike retainer, comprising in combination, a body formed to encircle a spike, material gripping members extending from the body, and a spike retaining element also integral with said body, said spike head retaining means including an upwardly and rearwardly extending projection, the line of juncture of said projection with the body being lower than the upper edge of the said body.

4. A spike retainer, comprising in combination, a body formed to encircle a spike, material gripping members extending from the body, a spike retaining element also integral with said body, said spike head retaining means including an upwardly and rearwardly extending projection, the line of juncture of said projection with the body being lower than the upper edge of the said body, and a pair of notches in the body, the bottom of each notch coinciding with the aforesaid lines of juncture.

5. A retaining device for spikes, comprising in combination, a tie plate, a spike, and a spike retainer, the body of said spike retainer formed to partially surround the spike between it and the corresponding opening in the tie plate, and means on the spike retainer adapted to automatically lock the spike in driven position.

6. A retaining device for spikes, comprising in combination, a tie plate, a spike, a spike retainer, the body of said spike retainer formed to surround the spike between it and the corresponding opening in the tie plate, means on the spike retainer adapted to automatically lock the spike in driven position, said means comprising a rearwardly extending projection integral with the retainer, and means for vertically straightening the same upon application to the tie plate.

7. A securing device for rails, comprising a spike, a band partially surrounding said spike, dilatable spurs integral with the band and positioned with respect to two sides of the spike, and penetrating edges formed on the band positioned with respect to the other remaining faces of the spike.

8. A securing device for rails, comprising a spike, a band surrounding said spike, dilatable spurs integral with the band and positioned with respect to two sides of the spike, and penetrating edges formed on the band positioned with respect to the other remaining faces of the spike, together with means integral with the band for locking the spike in driven position.

In testimony whereof I affix my signature.
HERBERT O. CRIPPEN.
